US00D436298S

(12) **United States Design Patent** (10) Patent No.: **US D436,298 S**
Tramontina (45) Date of Patent: ** Jan. 16, 2001

(54) **NAPKIN DISPENSER CARTRIDGE**

(75) Inventor: **Paul Francis Tramontina**, Alpharetta, GA (US)

(73) Assignee: **Kimberly-Clark Worldwide, Inc.**, Neenah, WI (US)

(**) Term: **14 Years**

(21) Appl. No.: **29/119,857**

(22) Filed: **Mar. 9, 2000**

(51) LOC (7) Cl. **07-06**

(52) U.S. Cl. **D7/631**

(58) Field of Search .... **D7/631; D6/512, D6/515; 211/45-48; 221/33-41, 45-55, 312 R; 312/34.4**

(57) **CLAIM**

I claim the ornamental design for a napkin dispenser cartridge, as shown and described.

DESCRIPTION

FIG. 1 is an oblique elevational view as seen from the left front edge of a napkin dispenser cartridge showing our new design;

FIG. 2 is a front elevational view thereof;

FIG. 3 is a left side elevational view thereof, the right side being a mirror image;

FIG. 4 is a rear elevational view thereof;

FIG. 5 is a top plan view thereof; and,

FIG. 6 is a bottom plan view thereof.
